UNITED STATES PATENT OFFICE.

ZENAS B. PIERCE, OF TAUNTON, MASSACHUSETTS, ASSIGNOR OF ONE-HALF
TO HORATIO L. CUSHMAN, OF SAME PLACE.

BUTTON-MACHINE.

SPECIFICATION forming part of Letters Patent No. 279,180, dated June 12, 1883.

Application filed March 2, 1883. (No model.)

To all whom it may concern:

Be it known that I, ZENAS B. PIERCE, of Taunton, in the county of Bristol and State of Massachusetts, have invented a new and useful Improvement in Button-Machines and Manufacture of Buttons, which will, in connection with the accompanying drawings, be herein-after fully described, and specifically defined in the appended claims.

10 This invention has for its object certain improvements in machines in and by which buttons formed of a plastic material are both molded into form, and have also the metallic eye inserted in such plastic body as the same 15 is being molded, my present invention being shown as in connection with a machine for which Letters Patent of the United States No. 243,723 were issued on my application on the 5th day of July, 1881, in which said machine 20 the partly-molded blanks of the button were placed in the hopper and were successively fed to the molding and eye-inserting devices, while my present invention has for its object the cutting of the blanks from a strip or ribbon of prepared pulp or other suitable material, and the insertion of the eyes and molding of the body during the same operation of the machine.

25 Figure 1 is a front elevation, showing my present invention as embodied in a machine embracing in other respects the features of my said former invention, said figure, with the exception of my said present improvements, being like Fig. 1 in my said former patent.

30 Fig. 2 is an enlarged detached perspective view, showing the blank-carrier, the feeding and punching devices. Fig. 3 is a partial view of the parts shown in Fig. 2 and taken from the same standpoint. Fig. 4 is a detached

35 vertical section, taken centrally and transversely through the parts shown in Fig. 3, and also showing some additional parts. Fig. 5 is also a detached vertical section, taken on the same line as is Fig. 4, but showing only a

40 portion of that figure, and showing the button as in the act of being molded. Fig. 6 shows in side elevation and in plan a section of a ribbon of pulp or other material, from which I cut the buttons.

45 In said several figures all the parts shown, which are duplicates of the parts shown in the

drawings in my said former patent, are marked to correspond with the marking in said patent, in order to facilitate such reference thereto as may at any time hereafter be by any person found necessary or desirable. 55

Having thus given an explanation of the several figures, I will now explain the various features of my present invention, at the same time referring to and explaining so much of the 60 coacting devices pertaining to said patent and shown in the drawings as may be requisite to a clear understanding of said last invention and its mode of operation.

In said views a^2 represents a bracket secured 65 to bed B, and formed with a longitudinal recess to receive and guide the ribbon b^2 , as shown in Figs. 1, 2, 3, 4, and upon said bracket is centrally secured a trimming-die, c^2 , which coacts with male punch 14 in cutting the blanks 70 from ribbon b^2 . Said male punch is seated in and carried by the vertically-reciprocating plunger e^2 , which moves in and is supported by central hub, f^2 , which is preferably formed as an integral part of bracket a^2 , as shown, and 75 is seated in a recess in bed B. Said plunger e^2 is pivoted in the front end of lever 12, which is pivoted in ears h^2 , formed beneath bed B, said lever being vibrated on pivot 13 in said ears by devices such as are shown and described 80 in said former patent, or by any desired means, such vibration of the lever being regulated to carry punch 14, not only through ribbon b^2 , but to such height that it will coact with other dies, to be described, for inserting the eye in 85 the blank and molding the latter.

The button-eye 16, which is cut from wire y , fed forward by rolls P against adjustable stop or gage 24, and is cut and bent by jaws k , over pin 16, in slide 6, and is also slightly 90 bent on anvil 17, when it is carried forward by said slide 6 until the end thereof is in contact with die-block 19, as shown in Figs. 4, 5, when eye 18, which remains on said pin 16, is held centrally over die C^2 and punch 14, as 95 shown in Fig. 3. All which operations, from feeding-wire y , forward by means of rolls P to carrying forward eye 18 over the punch 14, are fully described in connection with the drawings in said former patent, and may be 100 so accomplished, or by any other well-known means. As the eye 18 thus reaches its posi-

tion, lever 12 is vibrated to raise punch 14, which, in conjunction with die c^2 , cuts the blank or body 21 from ribbon b^2 , and carrying the same above the die, as shown in Fig. 5, 5 forces it upon the ends or prongs of the eye 18, thereby causing the latter to penetrate the blank, when by the united action of the punch, whose upper face is concaved to form a half-die, and the slide 6 and bar 19, each of which 10 constitutes a quarter-die, the blank is molded and set to form. When thus molded slide 6 is retracted, when a clearer, 23, (fully described in said patent,) sweeps the button from its seat in the end of punch 14 into discharge-chute 22, leaving the punch free to descend and repeat the operation. In Fig. 4 punch 14 is shown as at the moment of acting upon ribbon b^2 , while in Fig. 5 said plunger, as also the slide 6 and bar 19, are shown as 15 co-acting as an entire mold in molding the button after the insertion of the eye therein.

For the purpose of feeding the ribbon forward, at each descent of punch 14, a distance sufficient to allow the cutting of a blank or button-body therefrom, I arrange an angle-lever, l^2 , pivoted at its lower end in bracket a^2 , as shown, and carrying the pawl j^2 , depressed by spring k^2 , to engage and carry forward the ribbon, when said lever is itself moved forward. 20 A relief-pawl, l^2 , pivoted in ears of bracket a^2 and actuated by spring m^2 , serves to hold the ribbon firmly in position, while lever l^2 and its pawl make their retrograde movement.

For the purpose of actuating lever i^2 its upper end is pivotally connected with the lower end of lever n^2 , which is supported and vibrates upon pivot p^2 , secured in standard A. 35

In the upper end of lever p^2 is arranged a pin or trundle, t^2 , which travels in cam-groove u^2 , formed in disk G, carried by arbor C, through and by which arbor, either directly or indirectly, all the parts of the machine described in my said patent were actuated, as is therein described. By thus cutting the blanks 40 or bodies of the buttons successively from a ribbon automatically and positively fed forward in the order of the buttons being molded

and discharged from the machine, not only is the previous labor of the incipient molding of the blanks as formerly practiced avoided, but 50 the blanks are with unerring certainty supplied for uniting with the eye when it is in position to receive the blank, as described, this certainty of the presence of the blank in the molds at the desired point being a great improvement over the former method of supplying the blanks by means of a hopper, a conduit, or chute, and transmitting or impelling mechanism, all of which are by my present improvement rendered obsolete. 55

I claim as my invention—

1. In a button-machine, the combination of the ribbon supporting and guiding bracket a^2 , male punch 14, and die c^2 , with means to actuate said punch and to feed forward the ribbon so supported, and dies to insert eye 18 in the blank and to mold the latter, all substantially as specified. 60

2. In a button-machine, the combination of an eye-forming mechanism, an eye-inserting and button-body molding mechanism, and mechanism for supporting, guiding, and feeding the blank-supplying ribbon, and a cutting-punch arranged in conjunction with a die to cut the blanks from the ribbon, and to coat 70 in the molding thereof and the insertion of the eye therein, substantially as specified. 75

3. As an improvement in the manufacture of buttons, the herein-described method of successively and automatically cutting the blanks from an advancing ribbon, of suitable material in the order of such blanks being subjected to the eye-inserting and molding mechanism, substantially as specified. 80

4. The combination of grooved guiding and supporting bracket a^2 , punch 14, die c^2 , lever i^2 , with its actuating-pawl j^2 , the relief-pawl l^2 , and means to actuate both said punch and lever, substantially as specified. 85
